PULL TAB FOR CONTAINERS OR THE LIKE

Frederick J. Stec, Oak Lawn, Ill., assignor to Continental Can Company, Inc., New York, N.Y., a corporation of New York

Filed Jan. 3, 1964, Ser. No. 78,069

Term of patent 14 years

(Cl. D58—26)

FIGURE 1 is a top perspective view of a pull tab for containers or the like showing my new design;

I claim:

The ornamental design for a pull tab for containers or the like, as shown.
